A. HORVITZ.
BURGLAR ALARM AND PROTECTOR.
APPLICATION FILED APR. 12, 1917.

1,404,295.

Patented Jan. 24, 1922.

UNITED STATES PATENT OFFICE.

AARON HORVITZ, OF CHICAGO, ILLINOIS.

BURGLAR ALARM AND PROTECTOR.

1,404,295.

Specification of Letters Patent. Patented Jan. 24, 1922.

Application filed April 12, 1917. Serial No. 161,614.

To all whom it may concern:

Be it known that I, AARON HORVITZ, a citizen of the United States, and a resident of the city of Chicago, county of Cook, and 5 State of Illinois, have invented certain new and useful Improvements in Burglar Alarms and Protectors, of which the following is a specification.

My invention relates to improvements in 10 burglar alarm and protector mechanism, designed for use especially in office buildings.

The object of my invention is the production of a burglar alarm and protector mechanism of the character mentioned which will 15 be of high efficiency and which may be readily and easily operated by the office occupant seeking protection.

Other objects will appear hereinafter.

The invention consists in the combinations 20 and arrangements of parts hereinafter described and claimed.

The invention will be best understood by reference to the accompanying drawing forming a part of this specification, and in 25 which,

Fig. 1 is a partially diagrammatic perspective view of an office desk and building in connection with which is shown a burglar alarm and protector, embodying the 30 invention, and

Fig. 2 is an enlarged detail section through the sign or display device, included in the construction.

The preferred form of construction, as 35 illustrated in the drawings comprises an office desk 1, the top 2 of which is hinged at 3, to permit of swinging of the same to vertical position, as shown in dotted lines in Fig. 1. Said top 2 is normally held in vertical 40 position by means of helical torsional springs 4, said top, when in vertical position, being adapted to constitute a protector or shield for the office occupant against the bullets of a burglar or intruder entering the office. The member 2 is formed with side 45 flanges or leaves 5 which are adapted to more effectually guard the proposed victim, the arrangement being such that, when the desk top 2 is released and swung to vertical position, a three-sided inclosure or protector will be formed. When the desk top is 50 swung to vertical position, an opening 6 in the body of the desk is uncovered into which the intended victim may step for more effective protection. The desk top 2 is held

in lowered or horizontal position, as shown in full lines in Fig. 1, by means of a spring catch 7 carried by and depending from the top at one end, said catch being adapted for engagement with an electrically shiftable 60 bolt 8 with which cooperates a conventional solenoid coil arranged in an electric circuit 9. The arrangement is such that, when the solenoid coil is energized through closing of said circuit, the catch 7 will be released 65 to permit of upward swinging of the desk top. The catch 7 is also formed with a forwardly projecting handle 10 whereby the same may be manually flexed to effect release of the same.

At the front of the building in which the desk 1 is arranged is provided a display sign 11 having appropriate reading matter whereby, when said sign is uncovered or displayed, it will serve to advise passers-by at the street or sidewalk that a burglar is in the building and that help is wanted. The sign 11 is covered by a cover 12 which is hinged at 13, helical torsional springs 14 co-operating with said cover to normally hold 70 the same in upwardly swung or open position. Said cover is held in lowered or traversing position by means of a stop 15 adapted for engagement with a depending finger 16, carried at the free end of said 75 cover. The stop 15 is adapted to be retracted through energizing of a solenoid coil 17 arranged in a suitable housing 18, said solenoid coil being interposed in the circuit 9 in series with the solenoid coil, above described.

Also interposed in the circuit 9 is a switch 19 which is normally open. Said switch 19 will be conveniently located adjacent the desk 1 and preferably on the floor within the 80 space 6 so as to be adapted for engagement by the foot of the office occupant so that in case of sudden entrance of a burglar or other dangerous intruder, said switch may be readily and quickly closed in order to close 100 the circuit 9. Said closing of said circuit will simultaneously effect release of the desk top 2 and the sign cover 12, the former moving upwardly to protecting position and the latter swinging upwardly to display 105 the sign 11, in order to summon help.

In order to more effectually advise passers-by of the presence of a burglar in a building, an electric bell 20 is also employed which is arranged adjacent the sign 11, said electric 110

bell being interposed in an electric circuit 21. Also, the sign 11 will be of the transparent type with electric lights 22 arranged behind the same, said electric lights being 5 arranged parallel with the bell 20 in the circuit 21.

The circuit 21 is normally broken by a spring contact member 23 adapted, upon depression, to engage with a stationary contact 24 to close the circuit. Upon the cover 12 is provided a laterally projecting finger 25 adapted, when said cover is swung to open position, to engage with the contact member 23 in order to depress the same so as 10 to close circuit 21. Thus, it will be seen that, when the cover 12 is released and swung to open position, as above described, the circuit will also be closed to effect illumination of the sign 11 and sounding of the 15 alarm bell 20.

If desired, the electric circuit 9 and the mechanism cooperating with stop 15, as well as the springs 14, may be dispensed with and in lieu of these parts which serve the function of releasing the sign cover 12, and 20 swinging the same to open position, a cord 26 may be employed connecting the desk top 2 and said sign cover, said cord being passed around suitably arranged pulleys 27, 25 as will be readily understood. With this arrangement it will be seen that the cover 12 will normally hang by gravity in traversing position, and upon rocking of the desk top to vertical position, said cover, through 30 the medium of the cord 26, will be simultaneously rocked to raised or open position. Where the latter arrangement is employed, the electrical mechanism for releasing the desk top will also be dispensed with, said 35 top, with this arrangement being released by manual engagement with the handle 10.

While I have illustrated and described the preferred form of construction, for carrying my invention into effect, this is capable of variation and modification without departing from the spirit of the invention. I, therefore, do not wish to be limited to the precise details of construction set forth, 40 but desire to avail myself of such variations 45

and modifications as come within the scope 50 of the appended claims.

Having described my invention what I claim as new and desire to secure by Letters Patent is:

1. In an alarm system for buildings, an 55 electric bell interposed in a normally open electric circuit; an electric sign associated with said circuit comprising an elongated body; a cover for said sign hinged to one of the longitudinal edges of said body and 60 adapted, in one position, to cover said sign, and adapted, in another position, to expose said sign; a spring for moving said cover to and holding said cover in exposing position; a catch for retaining said cover in 65 said covering position; electrically-operated means for operating said catch to release said cover to permit of swinging of the same to exposing position; spring contact elements arranged adjacent said cover for 70 closing said circuit; and a laterally projecting arm carried at the outer end of said cover for actuating said contact elements to close said circuit when the sign is exposed, substantially as described. 75

2. In a burglar alarm system for a building, an alarm sign mountable on the exterior of building; a normally open electric circuit associated with said sign; a bell interposed in said circuit; a cover hinged to said sign; 80 means on said cover to close said circuit; a catch for retaining said cover closed; a second electric circuit including electrically operated means to withdraw said catch and release said cover; spring means for automatically forcing and retaining said cover open upon release of said catch, thereby exposing said sign and closing said first circuit; and means interposed in said first circuit to illuminate said sign. 85 90

In testimony whereof I have signed my name to this specification in the presence of two subscribing witnesses.

AARON HORVITZ.
